APPARATUS FOR INDIRECTLY LAYING ANTI AIRCRAFT GUNS

Original Filed March 29, 1926 2 Sheets-Sheet 1

Fig. 3.

Fig. 5.

UNITED STATES PATENT OFFICE.

WILLEM FREDERIK GROTENDORST, OF HELDER, NETHERLANDS.

APPARATUS FOR INDIRECTLY LAYING ANTIACRAFT GUNS.

Original application filed March 29, 1926, Serial No. 88,324, and in the Netherlands November 19, 1923.

Divided and this application filed August 7, 1926. Serial No. 127,961.

This application is a division of my co-pending application Serial No. 88,324, filed March 29, 1926.

This invention relates to apparatus for indirectly laying anti-aircraft guns of the type wherein data obtained from observations taken at points distant from the gun are transformed into data referring to the position of the gun.

10 This invention has for its object to provide a device whereby such transformation of data can be immedately and easily performed.

15 The present invention consists in an improved device for the laying of anti-aircraft guns, in which two charts are pivotally connected together, each chart having a ruler associated therewith, the charts and rulers being adapted to be set with the position 20 of the ruler on one chart dependent upon the setting of the ruler on the other chart, and so that upon one of the charts will be represented the projections of the target, the observation post and the gun upon a 25 horizontal plane, while upon the other chart will be represented the relation of the target and the gun with reference to the vertical plane through both.

30 The invention is illustrated in the accompanying drawings in some of its embodiments.

Fig. 1 shows in perspective the mutual relations between the observation post, the gun and the aircraft at two different moments.

35 Fig. 2 diagrammatically shows an apparatus with three rulers pivotable about a common point which is used for indirectly laying anti-aircraft guns.

40 Fig. 3 is a diagrammatic representation of the observation and gun positions, showing the gun as oriented after the initial observation.

45 Figure 4 is a top view of the apparatus indicated diagrammatically in Figure 2.

Figure 5 shows the graduated ring at the gun.

Figure 6 shows a special form of one of the rulers.

50 Figure 7 shows diagrammatically a modification in which the movements of the rulers are automatically dependent on one another.

55 In Fig. 1, K indicates the place at which the gun is mounted, P the observation post from which the aeroplane or other aircraft

V₁, is observed, and V₂ the required point of impact, i. e. the meeting point of aeroplane and projectile. A and B are the projections of V₁ and V₂ respectively on the horizontal plane through P and K. The target is assumed to move at a constant altitude. In order to be able to hit the aeroplane firing from K to V₂, it is necessary to have the following data:

(1) The angle D₃ + the angle of super elevation:

The angle D₃ = $\angle V_2KB$, as indicated in the drawing.

(2) The angle $\angle \beta_2$ indicating the direction of KB with regard to a fixed direction. It is preferable to use for this fixed direction the direction PK, as shown in the drawing.

(3) The timing of the fuse.

Figure 2 diagrammatically indicates a top view of an apparatus for use with anti-aircraft guns. MA₁A₂ indicates a fixed line on a fixed sector GA₂C whose centre is M. MC is so positioned that

$$\angle CMA_2 = \angle \beta_1 = \angle APK$$

of Figure 1, MA₁ corresponding with the distance PA of Figure 1. Through A₁ the line A₁E is drawn parallel with the line MC and of such length as to represent to a selected scale the distance PK of Figure 1. Hence ME corresponds with KA and $\angle A_2ME$ with $\angle P_1 = \angle PAK$. Then EF is drawn at right angles to ME, and EF = h of Figure 1, h being the height of the aeroplane = V₁A = V₂B. ME and MF are extended to meet the outside circumference at G and H. Then MF = KV₁ and $\angle GMH = \angle D_2 = \angle V_1KA$.

Supposing that the aeroplane is stationary at V₁, in this way the data are obtained for hitting V₁ from K. By the aid of $\angle \beta_1$, $\angle P_1$, $\angle D_2$ and distance MF which corresponds to KV₁ the gun may be given the required vertical and lateral direction as well as the necessary fuze setting. Of course, the angle of super elevation must be added to $\angle D_2$.

In Figure 3, P and K indicate the centres of the horizontal graduations of the instruments for measuring angles and distances at the observation post and at the gun. These graduations are oriented so that the 0°-180° graduations correspond with the connecting line PK. If on the graduation

of the gun $\angle \beta_1$ is marked out, for example, by means of an indicator Q , it is necessary, in order to train the gun upon V_1 , to mark out the angle P_1 with reference to Q .

5 All corrections relating to the lateral direction may be easily effected by not reading P_1 (Figure 2) at G but upon a displaceable indicator W_1 adjusted with reference to G so as to correct for the sum of 10 all lateral corrections.

By this means the difference between the angles AKP , BKP , NKP may be corrected mechanically.

The longitudinal corrections may also be 15 made simultaneously by arranging upon MG a displaceable scale W_2 which bears the range graduations, and which is adjusted with reference to the point E of the line A_1E so as to allow for the sum of all 20 range corrections. By this means the difference between the distance AK and BK may be corrected mechanically. If now EF is set upon the last-mentioned indicator W_2 , then $\angle D_2$ and MF are corrected 25 in the proper proportion, while by adjusting another indicator W_2 with reference to the point H so as to allow for the angle of super elevation, then the angle $D_3 +$ the angle of super elevation may immediately be 30 read. By marking out at the gun the corrected angle P_1 with reference to Q , the gun is laterally directed to V_2 , and by applying $D_3 +$ the angle of super elevation the gun is also laid on V_2 as regards the height. 35 The timing is also known from the corrected KV_1 .

Figure 4 shows the apparatus as it may be constructed for use. However, this is 40 only a constructional example which may be modified in details.

The rulers L_1 , L_2 , and L_3 are pivotally mounted at the centre M of the chart on the surface of which a fixed radial line MA is drawn and graduated from the point M 45 to a selected scale, 2 millimeters, for instance, representing 25 meters. The periphery of the chart is also graduated in degrees and minutes in each direction from the line MA . The ruler L_1 is read on the left part 50 of the periphery of the chart where the graduations run towards the left from $0^\circ-180^\circ$. This ruler corresponds with MG of Figure 2. The ruler L_2 corresponding 55 with MG of Figure 2 is read on the right-hand half of the periphery of the chart where the graduations run to the right, said 60 graduations being in degrees and minutes. The ruler L_3 corresponding with MH of Figure 2 is read finally on a scale having 65 graduations from $0^\circ-90^\circ$ and marked on the periphery of a quadrant S which is formed in one with the ruler L_2 and therefore rotates with this ruler. The various rulers in so far as may be necessary are provided

with means for making the corrections. On 65 the ruler L_1 itself distance graduations are provided, while to the lower part of the ruler and rotating with it an arc-shaped part B_1 is formed on which divisions in thousandth parts are provided both to the 70 right and to the left from a zero-point. Furthermore, a compass card W is fixed to the ruler L_1 and rotates with the said ruler so that after being once adjusted it always gives the correct indication of the lateral 75 direction. This is because the ruler L_2 which indicates the direction to which firing should take place (cf. Figures 1 and 2) then always comes to the correct point of the compass card, and may be provided with a 80 small indicator for easy reading.

The ruler L_2 is provided with a scale in the form of a longitudinally displaceable ruler 85 which is graduated in the same way as the fixed line MA . The construction permits of making the ruler very narrow, which is necessary to obtain a convenient design which shall allow for a small height of the aircraft target. On the right-hand side of the ruler L_2 a number of distance graduations 90 are provided increasing both above and below a zero-point, and the displaceable ruler 36 carries an index which may be set to correspond with a desired number of metres by sliding the displaceable ruler 95 36 along the ruler L_2 , and by this means longitudinal corrections may be effected. This arrangement corresponds with the displaceable indicator W_2 of Fig. 2.

The ruler L_2 has at its lower end a fixed 100 arcuate part B_2 , similar to that of the ruler L_1 . The arcuate part B_2 is subdivided into an upper half and a lower half, the upper half being provided on both sides of its zero-point with graduations in thousandth 105 parts or other suitable units, by which graduations an indicator W_1 , which is slidably mounted in said arcuate part B_2 , may be set to impart lateral correction. The lower half of the arcuate part B_2 is also provided 110 with graduations in thousandth parts or other suitable units, from which lateral corrections may be read.

A quadrant A or sector part S is fixed to the ruler L_2 and is provided with data indicating: 115

(1) The tangent of the angle of super-elevation that is the angle between the line of sight and the line of fire, for various angles of elevation; and various ranges; the 120 ratio of the sum of lost time and time of flight to the time between two observations;

(2) The timing or fuse setting for various angles of elevation and ranges.

When the ruler L_3 is set at the correct angle with reference to the ruler L_2 , then each point of the ruler L_3 corresponds to a 125 particular value of the required angle (D_3)

and the required distance, so that to each point of the sector S belong special data, which must be indicated on it.

The ruler L_3 is provided similarly to the 5 fixed line and the ruler L_2 , with graduations indicating distances of 25 metres. The lower end of L_3 is provided with an arcuate part B_3 extending only to the right, with graduations marked to the right from a zero-point, 10 on which the angle of super elevation may be set by the aid of the slideable indicator W_3 . If then the graduation of the periphery of the sector S is read at W_3 , then the sum of 15 the required angle of sight and the angle of super elevation is immediately obtained.

In the apparatus of Figure 4 a number of 20 lines are drawn parallel and to the left of the fixed line MA at short intervals and for the sake of clearness are preferably alternately black and red. These lines are here 25 used for setting the loose ruler L_4 parallel with the ruler L_1 , as hereinafter explained. The ruler L_4 has preferably the form as shown in plan view in Figure 4. The 30 points 37, 38 and 39 of the ruler are in a straight line. The distance 37—38 is arbitrary, the distance 38—39 being on the selected reduced scale equal to the distance from the observation post to the gun. On 35 the ruler L_4 a part from the centre equal in length to that between points 37 and 38 is clearly indicated, for instance, by making it another color. The length between points 38 and 39 of the ruler L_4 must be adjustable in order that it may be possible to use the 40 apparatus for various distances between the observation post and the gun. At the point 38 a recess or an opening is made in the ruler, in order to be able to read through it the divisions on the fixed line and to be able to adjust the point 38 on these divisions.

Finally in the apparatus shown in Figure 4 a fifth ruler or pin L_5 is provided by means of which the distance EF of Figure 2 may be marked out. Since EF is the measured height of the aeroplane, the ruler L_5 must be of extensible form and is preferably formed of telescoping parts. The arrangement is such that the centre line of L_5 is always perpendicular to the ruler L_2 (see Figure 2). For this purpose L_5 is substantially a T-square with an extremely small guiding part 45 by means of which the ruler L_5 can be displaced along the ruler L_2 and maintain its perpendicular relation thereto. The line 50 perpendicular to L_2 and passing through the point 41 of L_5 , and through the guide part 40, must also pass through the point 39 of L_4 (see Figure 2).

60 The manipulation of the apparatus shown in Figure 4 corresponds in principle with that of the apparatus of Figure 2. At the observation post P the observer begins by observing at a certain moment the height 65 and the distance of the aeroplane, as well as

its orientation with regard to the angle-measuring instrument. The angle β_1 is signalled to the gun and there the zero of the index Q is set on the graduated rim shown in Fig. 3 to correspond with this angle. The angle β_1 is also marked out on the apparatus of Fig. 4 by moving the ruler L_1 to the left from MA . Then the ruler L_4 is laid parallel to L_1 by setting the point 38 at the measured distance corresponding to PA (Figure 1) 70 on the fixed line MA and by placing the point 37 on the parallel line going through the end of the part of L_1 which has a distinctive color. Then the ruler L_2 is set to abut against the point 39 of the ruler L_4 , and the ruler L_5 set to the measured height of the aeroplane is placed against L_2 , opposite to the point 39, after which the ruler L_3 is set to abut against the point 41 of the ruler L_5 . At W_1 and W_2 (both still assumed to 85 be set at zero) the data may be read corresponding to the point V , of Figure 1. These data are required for finding the necessary corrections after the second measurement. The second observation takes place for 90 instance 10 seconds later, at which time other data are found which are read at W_1 and W_2 and on the auxiliary ruler 36. Now the corrections may be made, for which purpose use is made of the data indicated on the sector S where the point 41 is now positioned. The auxiliary ruler 36 is adjusted to allow 95 for the increase or decrease in the horizontal distance from the gun to the target during the lost time plus the time of flight as computed from the change of such distance during the ten seconds interval between observations.

Before the start of the firing, the total amount of the further longitudinal corrections has previously been determined, namely the corrections due to height of the barometer, wind, temperature of the gunpowder, and known range difference for the whole battery. This total correction is then also 105 imparted by means of the ruler 36. During the firing of course this ruler is also used to give the correction due to the vertical distance through which the projectiles fall during their flight.

110 The correction for the angle of super elevation is imparted by means of W_3 . The lateral corrections are effected as follows:— By the aid of the ruler L_4 there is determined the lateral angular displacement of the target during the time between successive measurements. This may be done mechanically by setting an indicator W_5 to mark the position of the ruler L_4 during the first measurement and then reading at the 115 second measurement the graduation of the arcuate part B_3 which is opposite to W_5 . The index arrow on the inner end of the ruler L_2 comes opposite a number on the 120 compass card which indicates the direction 125 130

of fire, and knowing the direction of the wind and the force of the wind and the lateral displacement determined by means of L_1 , the operator now immediately reads 65
 5 from a card system (which may be made in a very simple way) the total amount of all lateral corrections (i. e. correction for deflection displacement of the target, and wind), which must be imparted to L_2 . To
 10 this total amount, however, must be added the parallax increase or decrease, i. e. the difference in reading of L_2 between two measurements and then the whole must be multiplied by the ratio of the lost time plus
 15 time of flight to the time between two observations, which ratio is directly obtained by reading the sector S . The resulting final correction is imparted by the indicator W_1 . This method of imparting corrections may
 20 be carried out within the time between successive observations or measurements. W_1 is a displaceable indicator carried by the fixed chart and provided in order to indicate the increase or decrease of parallax
 25 between two observations. The angle read on the periphery of sector S as indicated by W_2 and the angle read on the periphery of the fixed chart as indicated by W_1 are communicated to the gun position, as well as the
 30 timing which is read on the sector S , if time fuses are used, or the distance read on the ruler L_2 . The gunner is then in possession of all necessary data and the gun may be fired. After the second measurement all
 35 necessary data may therefore be directly read from the apparatus. As the corrections change gradually the further determination of them is easy.

It is advisable to arrange the graduated 40
 40 rim at the gun and at the battery telescope in the way indicated in Figure 5, i. e. in two parts each running from $0-180^\circ$ in opposite directions. If the graduations should run from 0° to 360° the ruler L_2 would be
 45 brought beyond the fixed line MA as soon as the aeroplane passes the vertical plane going through the orienting line PK , which would make the reading of the other parts of the apparatus more difficult. But with
 50 the graduations arranged as in Fig. 5 all corrections read with the exception of the correction for deflection and the lateral correction for the wind must be taken in the reverse sense as soon as the aeroplane passes the plane in question and thus the alteration of the corrections can be easily effected by using the graduations for the gun at the other side of the zero-point, the correction tables being calculated to allow for this.
 55 Thus as soon as the aeroplane has passed the plane in question, the other graduations are used at the gun, and the other tables are used at the computing apparatus. With a view to allowing this, it is advisable to indi-

cate all of one set of corrections in black 65
 and the counter-corrections in red.

If the battery is at the left of the observation post the same apparatus may be used, provided care is taken that the zero-point of the graduated rim of the gun is on the same 70 side of the gun as the observation post.

The fixed line of the apparatus need not correspond with the direction from the observation post to the gun. If another fixed 75 line is taken, e. g. a certain magnetic bearing, it is only necessary to give to the ruler L_4 another form as, for example, that indicated in Figure 6. The points 37', 38' and 39' must then be adjusted on a reduced scale 80 in agreement with the relations existing in reality, for which purpose the ruler must be provided with three extensible points.

An important simplification in the manipulation of the apparatus may be effected by 85
 making the movement of the movable parts automatically dependent on each other. Such a device is indicated by way of example in Figure 7. In this device the ruler L_4 is so connected with the ruler L_1 , that when displacing the ruler L_1 the ruler 90
 L_4 is displaced parallel with L_1 and the point 38 always remains on the fixed line. For this purpose the ruler L_1 is connected by two rods 42 and 43 with an auxiliary ruler 49, in which the connections are such 95
 that L_1 , 42, 43 and 49 form a parallelogram, and by means of pivot connections 44, 45, 46 and 47 may carry out parallelogram movements. The rods 42 and 43 are parallel to the fixed line, and each has a slot 100 running in the longitudinal direction, in which slot guiding pins 50 and 51 of the ruler L_4 are guided. Then the movement of L_4 always remains parallel to L_1 , so that if L_1 is adjusted on β_1 , L_4 has only to be 105
 adjusted to place the point 38 on the measured distance PA (Figure 1).

Furthermore, the point 39 of the ruler L_4 is pivotally connected with the ruler L_5 , the latter being slidably mounted on L_2 . 110
 Moreover a resilient connection may be provided between L_5 and L_2 , so that the rulers L_1 , L_5 , L_2 and L_4 are automatically brought in their correct positions when L_1 is set 115
 and the point 38 of L_4 is brought to the correct place on the fixed line. All data may be directly read, whereby the lost time may be considerably diminished, and the number of men required in the detachment may be decreased. Also the possibility of mistakes by mutual displacement of the rulers is avoided.

The invention is not restricted to the constructive details which in this specification are only indicated by way of example, as various modifications may be made in these details. For example, in order to facilitate reading the longitudinal correction a meas-

uring tape may be used instead of an adjustable auxiliary ruler 36. The end of the measuring tape would be connected to the point 39 and said tape would be coiled up 5 resiliently near the end of the ruler. If the point 39 is displaced the measuring tape would be uncoiled or rolled up, so that at the ruler L_2 the distance may always be read, preferably at the same spot where 10 also the displacement of the ruler L_2 for the lateral adjustment must take place.

The way of making corrections may be modified in various ways. For example, all 15 corrections may be taken into account on the apparatus itself so that no card system is necessary. For this purpose the required data may be placed, for example, on the sector S; also instead of communicating the angle β_1 to the gun the corrected angle 20 β_1 may be communicated to the gun in which correction the correction for deflection may already be included. Also the angle β_1 might be taken as a correction to W_1 by which also β_1 need not be signalled to the 25 gun.

The spotting corrections can be mechanically imparted to the subsequent data obtained by adjusting the displaceable indicators W_1 and W_2 of Fig. 2.

20 I claim:

1. A device for laying anti-air craft guns, comprising two flat charts pivoted together, one of said charts having a line thereon extending radially from said pivot point and 35 graduated to a selected scale and the other of said charts having a line thereon extending radially from said pivot point, a ruler having two points thereon spaced by the observation point-gun distance to the selected 40 scale and slidable relative to said first chart with one point upon the graduated line of said chart and with the other point engaging the line on said other chart, a second ruler slidable relative to the second chart 45 and extending at a constant angle from the line on said second chart, and a third ruler pivotally movable about the point at which said charts are pivoted together.

2. A device for laying anti-air-craft guns 50 comprising a fixed chart having a line graduated to a selected scale, a ruler having two indicating points spaced to represent the distance between the observation point and the gun to the same scale, said ruler being adapted to be located with one of its indicating points coinciding with the graduation cor-

responding to the distance of the target from the observation point, and with its inclination corresponding to the angle subtended at the observation point between the 60 gun and the target, a second chart pivoted about the zero point of said graduated line on the first chart and having upon it a line also passing through said zero point, the second chart being adapted to be set so that the 65 line it carries will pass through the second indicating point of the first ruler, and a second ruler having two indicating points spaced to represent the height of the target from the ground to the selected scale, and 70 movable along and at an invariable angle with said line on the second chart, and with one of its indicating points corresponding with the second indicating point of the first ruler, whereby the inclination of the line in 75 the second chart to the graduated line of the fixed chart will indicate the parallax angle, and the location of the second indicating point of the second ruler upon the second chart will vary radially from the pivot point 80 to correspond with variations in the gun-target line.

3. A device for laying anti-aircraft guns as defined in claim 2, said second chart having indications thereon of various values of 85 the angle of super-elevation and time of flight.

4. A device for laying anti-aircraft guns as defined in claim 2, said second chart having a part movable radially along the line 90 thereon and graduated to the selected scale.

5. A device for laying anti-aircraft guns as defined in claim 2, an indicator laterally displaceable on said third ruler and which indicates upon the second chart the angle 95 of elevation at which the gun should be set.

6. A device for laying anti-aircraft guns as defined in claim 2, said second chart having an indicator laterally displaceable thereon to cooperate with said first chart in applying corrections in lateral direction. 100

7. A device for laying anti-aircraft guns as defined in claim 2, said second chart having an arcuate projection provided with a scale, and an indicator laterally displaceable relative to said first chart to cooperate with said scale on said arcuate projection for indicating variations in the parallax between successive observations. 105

In testimony whereof I have signed my 110 name to this specification.

WILLEM FREDERIK GROTEENDORST.
